UNITED STATES PATENT OFFICE.

JOHN H. SANOR, OF CANTON, OHIO.

DANGER-SIGNAL.

1,068,082.

Specification of Letters Patent.

Patented July 22, 1913.

Application filed November 28, 1908. Serial No. 464,937.

To all whom it may concern:

Be it known that I, JOHN H. SANOR, a citizen of the United States, residing at Canton, in the county of Stark and State 5 of Ohio, have invented certain new and useful Improvements in Danger-Signals; and I do hereby declare that the following is a full, clear, and exact description of the same.

The object of the present invention is to 10 provide means whereby accidents may be avoided in the movements of trains upon railway tracks and the invention has specific reference to the prevention of collisions regardless of the fact as to whether or not the 15 trains are approaching each other or one train following the other in close relationship. This object and purpose may be accomplished by the arrangement hereinafter described and by the devices shown in the 20 accompanying drawing making a part of this specification.

In said drawings:—Figure 1 is a view showing a section of railway track and illustrating the forward axles of two cars, but the 25 trucks are not shown, also showing a diagrammatic arrangement and connection for the light signals and batteries and relays and dynamo or generator. Fig. 2 is a perspective view showing a portion of one of the 30 railway rails and the insulation as located at intervals, whereby blocks or sections of track of any desired length may be produced, also showing a spring contact plate in proper relative position.

Similar numerals of reference indicate 35 corresponding parts in the figures of the drawing.

In the accompanying drawing, 1 represents the railway rails which are of the 40 usual construction, but in order to carry out the objects and purposes of the invention the railway track is divided into blocks or sections, the rails being insulated at the terminals of the sections. The object of this 45 is to prevent a waste of current and at the same time produce light signals along the railway track at comparatively short intervals. At the inner sides of the railway rails 1 are located a series of spring contacts 2, 50 which are so formed and located that when the wheels of a locomotive or cars pass said spring contacts they will be brought into close contact with the railway rails by the flanges of the wheels which contact closes a 55 circuit providing that at the same time the spring contacts are brought into contact with

the opposite rail in the section but the wiring is so arranged as to the sections, that the circuit will not be closed unless the spring contacts are brought into engagement 60 with both rails in the section. In order to provide for this arrangement or more specifically speaking to provide against the closing of the circuit except at such times when two trains are approaching each other on 65 the same track, or two trains are closely following each other on the same track in a given section the spring contacts 2 are coupled up in series by means of the wires 3 each of the series being longer than the 70 length of any train designed to pass over the road, and are so formed for the purpose of preventing any flickering of the signals and at the same time keeping one or more of the spring contacts 2 in proper contact 75 with the rail during the entire time the train is passing the given series. It will also be understood that the distance between the different series of spring contacts should be greater than the length of any train so that 80 a single train will not actuate or close the circuit by coming upon two series at one time, which series are staggered and the oppositely staggered series of contact plates must be brought into engagement with both 85 rails before the circuit is closed. It will therefore be understood that if the space between the series is not greater than the length of a single train, the train would 90 close the circuit and show the danger signals when unnecessary and when there was no danger of accident.

For the purpose of showing a given section electrically connected I have illustrated the wires 4 which are simply for the purpose of showing a continuation of electric connection which actually takes place in the railway rails when the current is on and the wires 4 to take up the intervening space or the gap shown in the section. For the purpose of cutting off the current as between the sections the rails of the track are insulated as shown at 5, by which arrangement no current is to pass from one insulated section to another through the railway track 105 but may be carried by the wires.

In use one battery 6 and one source of lighting current, such as a storage battery or a generator 7 and one relay 8 must be provided for each section or block which 110 parts are located between the insulations 5 of one rail of the track, but the opposite

rail of the track may be provided with insulation midway between the insulation of the opposite rail.

Let it be supposed that a pair of axles 5 are in such position that the wheels bring the spring contacts 2 into contact with both rails at the same time; the circuit is now closed, and this may occur by two trains approaching each other or two trains closely 10 following each other in the same section. Now, starting at the battery 6 the current may pass through the conductor 9 through the relays 8 into the line wire 10, the switches 11 and 12 being normally open and thence 15 to the conductor 13 and into the wire 3, thence across the truck through the axles 14 through the track and to the rail and wire 3^a and thence to the return conductor 15 into the return side of the battery. This 20 current closes the armature 16 and the circuit breaker 17 and the current is conveyed through the conductor 18 to the line wire 19 and the short conductor 20 and thence to the line wire 21 and the light wires 22, re- 25 turning on the line wire 21 through the conductor 23 to the generator 7, the generator being connected by the wire or conductor 24 which leads to the circuit breaker 17 and the current conveyed from the generator to the lights. If in the event a signal 30 is desired independent of any trains as for instance a land slide has occurred or a bridge burned or any other obstruction has occurred to the train or trains the switch 35 25 may be closed and the current shunted past the circuit breaker 17 and conveyed over the same wires as above described. When it is desired to use the battery circuit the switch 11 may be closed. The closing 40 of switch 11 causes current from the battery to energize the relay magnets 8, thereby actuating the circuit breaker switch 17 and thus connecting the generator with the line wires to light the signals. If in the event 45 an obstruction is placed upon the track and if for any cause it should be desirable to turn the signals on by track walkers or other authorized persons the switch 12 is closed, which switch may be located at the 50 side of the track within the block or section, or a series of switches may be employed and spaced from each other for convenience in cases of emergency. The closing of the switch 12 will conduct the battery current 55 through the conductor 27 the wires 3^a and

the return battery wire 15. For the purpose of cutting in or out, all of the series of lights of a given section or block division switches such as 28 may be employed and opened and closed in the usual manner. 60

The groups of spring contacts should be of such a length that a passing train will take up the necessary current for a sufficient time to actuate the signal. These groups may be of any desired length, that is to say 65 a mile or any fractional part thereof. The exact length is immaterial.

Having fully described my invention what I claim as new and desire to secure by Letters Patent, is—

70

1. In a signal device the combination of a railway track, each of the rails of which is divided into sections by insulation, the insulation in the respective rails being arranged in staggered relation, groups of 75 spring contacts arranged along the track, the individual members of each group being connected in series and alternate groups arranged adjacent to the insulation in the opposite rails of the track and in the path of 80 the wheels of the train, a battery and conductors leading from opposite sides of the battery to adjacent groups of spring contacts, a magnet included in one of said conductors and an electrically operated signal 85 controlled by said magnet.

2. In a signal device, the combination of a railway track, each of the rails of which is divided into sections by insulation, the insulation in the respective rails being arranged in staggered relation, groups of 90 spring contacts arranged along the track, the individual members of each group being connected in series and alternate groups arranged adjacent to the insulation in the 95 opposite rails of the track and in the path of the wheels of a passing train, a battery and conductors leading from opposite sides of the battery to adjacent groups of spring contacts, a magnet included in one of said 100 conductors and electrically operated signals controlled by said magnet, substantially as and for the purpose specified.

In testimony that I claim the above, I have hereunto subscribed my name in the 105 presence of two witnesses.

JOHN H. SANOR.
